(57) **CLAIM**

The ornamental design for a front of a dishwasher, as shown and described.

DESCRIPTION

FIG. 1 is a perspective view of a front of a dishwasher according to a second embodiment of my design;

FIG. 2 is a front elevational view of the front of the dishwasher according to the second embodiment;

FIG. 3 is a right side elevational view of the front of the dishwasher according to the second embodiment;

FIG. 4 is a top plan view of the front of the dishwasher according to the second embodiment; and,

FIG. 5 is a bottom plan view of the front of the dishwasher according to the second embodiment.

While FIG. 3 illustrates the right side elevational view of the front of the dishwasher, the left side elevational view of the front of the dishwasher would be the mirror image.

While FIG. 3 illustrates the right side elevational view of the front of the dishwasher according to the second embodiment, the left side elevational view of the front of the dishwasher according to the second embodiment would be the mirror image.

In each of the Figures, the front of the dishwasher is shown positioned on a broken line representation of a dishwasher which is for illustrative purposes only and forms no portion of the claimed invention.
